UNITED STATES PATENT OFFICE.

WILLIAM HENRY BLACKBURN AND RICHARD BLACKBURN, OF NOTTINGHAM, ENGLAND.

CIRCULAR-KNITTING MACHINE.

1,084,194.

Specification of Letters Patent. Patented Jan. 13, 1914.

Application filed August 6, 1909. Serial No. 511,526.

To all whom it may concern:

Be it known that we, WILLIAM HENRY BLACKBURN and RICHARD BLACKBURN, subjects of the King of Great Britain, and residents of Nottingham, England, have invented certain new and useful Improvements in Circular-Knitting Machines, of which the following is a specification.

This invention relates to improvements in circular knitting machines with multi-feeders, and its object is to produce on such machines, knitted fabrics with vertical stripes in two or more colors.

Referring to the drawings, Figure 1. is an interior view or development of part of the cam cylinder, showing the disposition of the cams and the needles. Fig. 2. is a vertical section of the cam and needle cylinder of the machine. Figs. 3, 4 and 5 are views showing the different forms of needles employed.

Like letters indicate like parts throughout the drawings.

According to this invention the circumference of the machine is divided into an equal number of sections, each of which is provided with its own thread feeder, sinker, and needle operating cams, the whole of which are reciprocated, so that each thread 25 is always supplied to and knitted on the same section or group of needles in the machine.

Every alternate section in the machine is filled with needles A (see Fig. 1.) each provided with an upper butt A¹, that is a butt situated some distance up the needle stem, and the remaining sections with needles B each provided with a lower butt B¹, that is a butt near the lower part of the needle 35 stem. One of the needles A with an upper butt A¹ is shown detached in Fig. 3. and one of the needles B with a lower butt B¹ is shown in Fig. 4.

The joining needles C at the ends of the 45 sections, that is those needles which are situated at the points where one section ends and another begins, are (as shown more clearly in Fig. 5.) each provided with two butts C¹, that is, both upper and lower, but the said 50 butts C¹ of these needles C are as shown, made shorter than the butts A¹ B¹ of the other needles.

The needle operating cams are arranged

in two tiers in the reciprocating cam-ring D, every alternate set E E¹ E² (see Fig. 1.) 55 being situated in the upper tier, and the remaining sets F F¹ F² in the lower tier. The former correspond to and actuate the groups of needles A, with upper butts A¹, while the latter correspond to and actuate the 60 groups of needles B with lower butts B¹.

By employing needles with upper and lower butts in alternate sections of the machine, and arranging the cams as described, space is provided for each set of cams to 65 run out of its own section into the one next to it on either side, without operating the needles in the latter sections. Referring to Fig. 1. the cam-ring D has just completed its movement to the left, and the sets of 70 cams are all on the left of the groups of the needles which they operate. The cam-ring D will now move to the right as indicated by the arrow, and on the completion of this movement, the cams shown on the 75 left of Fig. 1. will have moved into the same position as the cams shown on the right.

The knitting cams E in the upper tier are of full thickness, and their inner faces are flush with the inner face of the cam-ring D, 80 (as shown in Fig. 2.). The clearing cams E¹ E² on either side of the knitting cams E, are only about half the thickness of the knitting cams E, and their inner faces are consequently sunk below the inner face of 85 the cam-ring. The knitting cams E not only actuate the needles A with upper butts A¹, but they engage with the upper butts C¹ of the joining needles C in their respective sections, and actuate the latter as well. 90 The clearing cams E¹ E² being of reduced thickness or sunk, do not engage with the short upper butts C¹ of the needles C, but engage with the butts A¹ of and clear the needles A every course. 95

The knitting cams F in the lower tier, are the same as and act in a similar manner to the knitting cams E previously described, that is to say, they engage with the butts B¹ of and actuate the needles B; they also 100 engage with the lower butts C¹ of and actuate the joining needles C in their respective sections. The clearing cam F¹ on the left of the knitting cams F is of reduced thickness or sunk; it will therefore engage 105 with the butts B¹ of and clear the needles

B, but will not engage the lower butts C¹ of the joining needles C. The clearing cams F² on the right of the cams F may be full thickness and flush with the inner face of the cam-ring D, in which case they engage with the lower butts C¹ of and clear the joining needles C, as well as the needles B every course, or in order to clear the joining needles every other course, these cams are constructed as shown in the drawings. In this case the upper part of the cam F² is cut away or reduced so as to form a lower step at F³, (see Fig. 2.) and a tumbler G is pivoted in a recess at one end, as shown more clearly in Fig. 1. When the cams are moving to the left, the top of the cam F² acts on the butts B¹ of the needles B and clears them, while only the lower step F³ of said cam engages with the short lower butts C¹ of the joining needles C; and this raises the latter, but not high enough for them to clear their loops. In moving to the right, the tumbler G is turned up by the needle butts, and the joining needles C are in this case raised and cleared as well as the ordinary needles.

The general action is as follows:—The needles A with upper butts A¹ in each of the sections, are caused to knit each motion by the action of the knitting cams E, and are cleared by one or the other of the clearing cams E¹ and E². The needles B with lower butts B¹ in the remaining sections, are caused to knit each motion by the knitting cams F, and are cleared by the clearing cams F¹ and F², the former when moving to the right, and the latter when moving to the left. The joining needles C at the ends of the sections, are actuated by both the upper and lower knitting cams E and F, and they thus knit twice to the others once, each forming the first needle in one section, and the last in the next section, taking both threads. These needles C are only cleared by the clearing cam F², and when of the construction shown, it raises the joining needles C high enough to take the yarn, but not high enough for them to clear their loops when moving to the left, but the tumbler G comes into action and raises them to the full extent when moving to the right, so that these needles C are only cleared every other course. These joining needles C thus tuck and knit alternately, so that they each hold the thread from the section on one side, until they have taken the thread from the section on the other side, and then clear both. With this system of working a perfectly straight joining line is obtained at the points where the respective strips of material, knitted on the different sections, are joined together.

The needle cam-ring D is reciprocated through the requisite angular space by any well known mechanical contrivance, and the

sinker cam-ring H (see Fig. 2), which is provided with a set of cams for each section, is connected to the needle cam-ring D by a well known lost motion device, so that the needle cam-cylinder has always the requisite lead of the sinker cam-ring, as is well known.

The thread feeder may comprise a ring J provided with a hole J¹ for each thread, said holes being spaced the required distance apart, and as each thread may be of a different color, the various colored effects which can be produced in the fabric is very considerable.

The thread feeder ring J described, rests in a seat provided for it in the sinker cam-ring H, and is connected to the reciprocating needle cam-ring by means of any well known friction driving device. Fixed stops are provided to bring it to rest before the cam cylinder at the end of each movement in either direction, so that it always starts with the requisite lead or in advance of the needle cams.

What we claim as our invention and desire to secure by Letters Patent is:—

1. In a circular knitting machine for making vertical striped fabrics, the combination of a reciprocating cam ring, reciprocating thread feeders, ordinary needles arranged in groups those in alternate groups all having upper butts and those in the remaining groups all lower butts, joining needles at the ends of the groups with both upper and lower butts shorter than those of the ordinary needles, needle operating cams arranged alternately in upper and lower tiers in the cam ring, knitting cams in both tiers that will operate both the ordinary and joining needles, sunk clearing cams in one tier that will clear the ordinary needles, sunk clearing cams in the other tier that will clear the ordinary needles, stepped clearing cams adapted to clear the ordinary needles and raise the joining needles high enough to take the thread, and means for clearing the joining needles every alternate course, substantially as described.

2. In a circular knitting machine for making vertical striped fabrics, the combination of a reciprocating cam ring, reciprocating thread feeders, ordinary needles arranged in groups those in alternate groups all having upper butts and those in the remaining groups all lower butts, joining needles at the ends of the groups with both upper and lower butts shorter than those of the ordinary needles, needle operating cams arranged alternately in the upper and lower tiers in the cam ring, knitting cams in both tiers that will operate both the ordinary and joining needles, sunk clearing cams in one tier that will clear the ordinary needles, sunk clearing cams in the other tier that will clear the ordinary needles, stepped

clearing cams adapted to clear the ordinary needles, and raise the joining needles to take the thread, and a tumbler cam pivoted in each of said stepped clearing cams adapted 5 to raise and clear the joining needles every alternate course, substantially as described. In testimony whereof we have signed our

names to this specification in the presence of two subscribing witnesses.
